H. MEYER

BOAT

Filed April 14, 1926

Inventor:
Hermann Meyer
by J. B. Sieger, Atty.

UNITED STATES PATENT OFFICE.

HERMANN MEYER, OF BERLIN, GERMANY.

BOAT.

Application filed April 14, 1926, Serial No. 102,011, and in Germany February 14, 1925.

My invention relates to improvements in boats, and more particularly in boats of the type in which the hull comprises a pneumatic tubular member ordinarily in the form of an elongated ring adapted to be expanded and collapsed. The object of the improvements is to provide a boat of this type which has a high degree of stability, and which has a comparatively rigid hull,

10 With this object in view my invention consists in securing rigid bodies preferably made from veneer or other light and strong material to the ends of the pneumatic ring, the said bodies being in the form of the bow or stern of the boat. In the preferred construction the said bodies are provided with means for securing a keel thereto.

For the purpose of explaining the invention an example embodying the same has 20 been shown in the accompanying drawing, in which the same reference characters have been used in all the views to indicate corresponding parts. In said drawing,

Fig. 1, is an elevation of the boat,

25 Fig. 2, is a top-plan view,

Fig. 3, is a bottom view,

Fig. 4 is an end view, and

Fig. 5, is a section taken on the line 5—5 of Fig. 1.

30 In the example shown in the drawing the hull of the boat comprises an elongated pneumatic annular tube 1 provided with a valve 2 for expanding the same by means of compressed air. The length of the annular tube is nearly equal to the length of the hull, and its breadth is equal to the breadth of the hull. The bottom 3 of the boat consists of a plate of rubber, canvas, raw hide, or the like, glued or otherwise secured to the bottom of the pneumatic tube, and an inner lining 4 preferably made from boards or slats of wood arranged in the manner of Venetian blinds, the said lining imparting a certain rigidity to the bottom.

To the end faces 5 and 6 of the tube a 45 rigid bow 7 and a rigid stern 8 are glued or otherwise secured, which stern and bow are in the form of tapering hollow bodies made from veneer or similar light and strong material. By thus providing the 50 hull with a stern and a bow the resistance of the water is reduced, and the hull is braced.

I claim:

1. A boat hull comprising an inflatable 55 and expandable annular tube and bow and stern members, each open at the inner end and tapering toward the outer end, the ends of the said inflatable tubes being arranged in the open inner ends of said bow and 60 stern members and secured thereto.

2. A boat hull comprising an inflatable and expandable annular tube and bow and stern members, each open at the inner end and tapering toward the outer end, the ends 65 of the said inflatable tube being arranged in the open inner ends of said bow and stern members and secured thereto, said hull also comprising a bottom secured to the bottom of said expandable tube. 70

3. A boat hull comprising an inflatable and expandable annular tube and bow and stern members, each open at the inner end and tapering toward the outer end, the ends of the said inflatable tube being arranged in 75 the open inner ends of said bow and stern members and secured thereto, said hull also comprising a bottom secured to the bottom of said expandable tube, and an inner lining on said bottom and arranged between 80 the opposing inner sides of said inflatable tube.

In testimony whereof I hereunto affix my signature.

HERMANN MEYER.
